MARION B. THOMPSON, OF LOUISVILLE, KENTUCKY

TRAFFIC SIGNAL SYSTEM

Application filed May 8, 1930. Serial No. 450,607.

This invention relates to traffic signal systems for regulating vehicular traffic at street intersections. At the present time street intersection traffic signal regulations vary quite widely in the different communities and quite often the regulations in the congested areas of any particular community differ from those employed in the other areas of the same community. Particularly is this true in connection with the permissible turns at the various street intersections. The regulations in this respect differ more widely than in any other phase of traffic control with the result that a person traveling from one community to another is often at a loss to know how to proceed.

The three light, three color—green, yellow and red—traffic signal has been adopted by practically all communities using signal lights and has come to be considered as the standard signal. With this type, the generally accepted or standard regulations are that the green or "go" light is a signal permitting movement in any direction except as modified by the turn regulations, the red or "stop" light is a signal prohibiting movement in any direction except as modified by the turn regulations while the yellow or "caution" light is a signal of the approaching change of lights. In some communities additional lights are employed to inform the traveler as to the permissible or non-permissible turns as the case may be. Naturally additional lights require additional control apparatus, larger signal supports and are otherwise considerably more expensive than the standard three light signal alone. A less expensive arrangement utilized by other communities to inform travelers of permissible turns consists in the use of printed signs in connection with the standard three light signal. The use of printed signs, however, is objectionable inasmuch as they must be placed out of the line of vision from the traffic flow to the signals where they are very apt to be overlooked. Consequently they are not highly efficient in the prevention of accidents or traffic regulation violations. They are also objectionable because of their unsightliness which is accentuated by the conspicuous posi-

tion in which they must be placed to accomplish their purpose even inefficiently. Furthermore such signs must be printed in big bold type in order to be readable thereby necessitating comparatively large signs at corners having more than one turn regulation such, for example, as corners where left turns are not permitted on the go signal and right turns are permitted on the stop signal. Obviously an increase in the size of the signs further accentuates their unsightliness and, at the same time, requires heavier and more expensive supports than otherwise in order to meet the increase in weight and wind resistance.

The principal object of the present invention is to provide a traffic signal system, utilizing the standard three light signal, which will fully inform travelers of the permissible or non-permissible turns at each specially regulated intersection, and, which will accomplish this object without the use of printed signs, additional lights or other similarly objectionable or expensive equipment.

A further object is to provide a traffic signal system of the character stated in which the standard three light signal units of existing systems may be utilized without requiring any change in the position, location, or operation of the various units comprising the system and without entailing any material expenditure of time or money.

Generally stated, the invention consists in arranging in the line of vision from the traffic flow to the non-standard turn-regulated stop and/or go signals of a standard three light signal, a direction indicating symbol to indicate positively the permissible turn and thereby negatively show the non-permissible turn. By placing the direction indicating symbol in the line of vision as stated, a traveler approaching a non-standard turn-regulated intersection and looking at the turn-regulated signal must, of necessity, see the indicator. Consequently he is instantly informed of the turn regulation and thus not required to hesitate and search for printed signs or other sources of information. It should be understood that the direction indicating symbols need only be used in connection with signal

units located at street intersections having one or more non-standard turn regulations. Naturally at the intersections having the generally accepted or standard regulations, the 5 traveler knows instantly, upon seeing the green signal, that he is permitted to make either turn, and, upon seeing the red signal, that he is prohibited from making any turn.

The invention will, perhaps, be better understood by reference to the accompanying drawing, wherein:

Figure 1 is a front view of a standard three light signal unit embodying the invention; and

15 Figure 2 is a diagrammatic view showing the invention as applied to a system of standard three light signal units controlling the traffic flowing in one direction across a series of intersections.

20 The direction indicating symbol may, in accordance with the invention, be of any suitable form and be arranged in any suitable manner in the line of vision between the flow of traffic and the particular signal to which

25 it may apply. Preferably the indicator is made of triangular form as shown at 1 in Figure 1 and is applied directly to the lens 2 of the signal light as by painting it thereon or pasting a suitable triangular form there-
(30) to. The lens 2 is positioned at the proper signal light of its particular signal unit in a manner such that the apex 3 of the symbol points in the direction of the permissible turn.

The diagrammatic layout shown in Figure 35 2 illustrates the application of the invention to a standard three light traffic signal system. In this case a series of vehicles 4, 5, 6, and 7 are shown as traveling along the same street in the direction of the arrow A, each vehicle 40 being about to cross a different intersection. Each of the intersections is controlled by a different three light signal unit, the go or green, caution or yellow, and stop or red, signals of each unit being indicated respectively by the letters G, Y and R.

45 The first intersection that is to say the one which vehicle 4 is about to cross, is shown as a standardly regulated intersection. The driver of this vehicle, upon looking at the signals, will immediately know: if the signal be green, that he may go straight ahead or make either turn; and, if it be red, that he is not permitted to move in any direction.

50 The driver of the next vehicle (5) by looking at the signal, will see the direction indicator 1 on green only, and, since it points to the left, he will immediately know: if the signal be green, that he may go straight ahead or turn to the left only; and, if it be red, that he is not permitted to move in any direction. Thus this driver, simply by looking at the signal, a required act in any signal system, is instantly and fully informed of

the non-standard regulations controlling the flow of traffic at this intersection. The signal thus operates to prevent the driver from making a wrong turn whether or not he is aware of the fact that the cross street is a one way street permitting travel to the left only. Furthermore it will tend to make him aware of the fact that the cross street is a one way street without requiring the use of signs to point out such fact.

70 At the next intersection, the cross street is shown as another one way street permitting travel to the right only. In this case the driver of the vehicle 6 by looking at the signal, will see direction indicators 1 pointing to the right on both red and green, and consequently he will immediately know: if the signal be green, that he may go straight ahead or make a right turn only; and, if the signal be red, that he is permitted to make a right turn. The advantages of the indicator with respect to the one way phase of the intersection, are again apparent.

75 By looking at the signal of the last intersection, the driver of the vehicle 7 will see a direction indicator 1 pointing to the right on red only, and consequently he will immediately know: if the signal be green, that he may go straight ahead or make either turn; and, if the signal be red, that he is permitted to 80 make a right turn.

85 The foregoing is, of course, merely illustrative of the application of the invention and is made to bring out the advantages of the invention and is not to be construed as a limitation thereon. It is apparent from this illustration that the invention may be easily, quickly and inexpensively applied to existing systems utilizing standard three light signal units and that it eliminates the use of both 90 unsightly signs and expensive additional light equipment. It has further advantages in that it is easily understood and does not obscure the signal lights although positioned directly in the line of vision.

105 95 Having described my invention, I claim:

1. In combination, a traffic light signal unit of the standard type having differently colored signals for the standard regulation of traffic, and means permanently associated with one of said signals modifying the light emission therefrom for indicating the only turn permissible on that signal.

110 115 120 125 2. In combination, a traffic light unit of the standard type having different colored signals for the routine regulation of traffic, and means permanently associated with one of said signals modifying the light emission therefrom for indicating a special turn regulation applying to that signal.

130 In testimony whereof I hereunto affix my signature this 6th day of May, 1930.

MARION B. THOMPSON.
